UNITED STATES PATENT OFFICE.

ELMO J. BUSH, OF EAST ST. LOUIS, ILLINOIS.

PORTABLE BATHING APPARATUS.

1,877,803.

Specification of Letters Patent. Patented May 10, 1921.

Application filed August 27, 1920. Serial No. 406,284.

To all whom it may concern:

Be it known that I, ELMO J. BUSH, a citizen of the United States, residing at East St. Louis, in the county of St. Clair 5 and State of Illinois, have invented certain new and useful Improvements in a Portable Bathing Apparatus, of which the following is a specification.

This invention relates to water heating 10 apparatus, and has for one of its objects to provide a portable generator, a portable water tank coupled to the generator, and a portable bath tub.

With these and other objects in view, the 15 invention consists in certain novel features of construction as hereinafter shown and described and then specifically pointed out in the claims, and in the drawing illustrative of the preferred embodiment of the 20 invention.

The figure represents the improved apparatus, showing the tank in vertical section.

The improved apparatus includes a generator 25 represented as a whole at 10 and adapted to be disposed upon any suitable means for heating the water therein, for instance a cooking stove or range represented conventionally at 11.

30 Inlet and outlet metal pipes 12 and 13 are connected to the generator 10 near the top and bottom, as shown, these pipes being of sufficient length so that sections of rubber hose 14 and 15 may be attached thereto 35 at a safe distance from the stove or other source of heat.

The water tank portion of the improved apparatus comprises a tank or drum 16 of any required size or capacity and supported 40 for movement from place to place as required.

The support for the tank includes a lower ring or band 17 preferably formed from an L-bar bent to circular shape and the ends 45 welded or riveted, with the horizontal web directed inwardly to form a rest for the tank. The tank support also includes an upper band 18 surrounding the tank and coupled to the lower band 17 by a plurality 50 of straps or standards 19.

The standards 19 are likewise connected at suitable intervals by intermediate bands or hoops 20, and one of the standards is supplied with a hose supporting hook 21.

55 A pipe 22 is connected through the bottom of the tank, and provided with a con-

trolling valve 23, and with a section of hose 24 coupled to the outer end of the pipe, the hose being engaged over the hook 21 when not in use.

The tank 16 is provided with a removable cover 25, preferably hinged thereto as at 26, and having an opening provided with a supplemental cover 28.

The tank is supplied with water in any 65 suitable manner. If employed where hydrant water is available, the water will be supplied through a section of hose 29, inserted at one end through the opening in the cover 25 with the other end coupled to 70 the source of supply not shown, the member 29 having a controlling valve shown at 30.

If employed where hydrant water is not available, the cover 25 will be opened and the tank supplied by pails or buckets.

The tank 16 is provided with a hose connection 31 including a controlling valve 32 at its lower end and a similar hose connection 33 including a controlling valve 34, intermediate the ends. The hose section 14 80 is coupled to the connection 31, while the hose section 15 is coupled to the connection 33.

By this means it will be obvious, that when heat is applied to the generator 10, 85 the water will be caused to rapidly circulate through the generator and tank, and the water in the tank uniformly and rapidly heated.

Attached to the lower annular member 17 90 are a plurality of legs 35 having casters 36 at their lower ends. By this means the tank and its supporting structure or crate are easily movable from place to place.

The bath tub portion of the improved apparatus is of the usual form and represented as a whole at 37. The bathtub is portably and detachably supported in a crate or frame similar to the crate or frame of the tank, and comprises a lower rectangular 100 member 38 preferably formed of an L-bar with the horizontal web directed inwardly and forming a seat for the tub. The tub support also includes a rectangular band 39 encompassing the tub near the top and 105 coupled to the member 38 by a plurality of straps 40.

Attached to the member 38 at its corners are leg members 41 each having a caster 42 to enable the tub to be moved from place to 110 place.

The discharge of the tub is represented at

43 and includes a plug member 44 connected by a chain 45 to the tub, in the usual manner.

A section of hose 46 is attached to the discharge 43, to enable the contents of the tub 5 to be discharged at a convenient distance from the tub, the hose 46 being supported by suitable hooks 47 on the tub frame, as shown when not in use.

The hose section 24 is employed to supply 10 the heated water from the tank to the tub, and the hose is engaged over the hook 21 when not in use.

By this simple arrangement, a convenient portable bathing apparatus is produced 15 which may be carried to any convenient room containing a stove or other heating appliance of any character, and a water main spigot. By this means a house not supplied with a bath room of the ordinary construction may be supplied with convenient bathing facilities. After the bathing 20 operation, the tub may be wheeled to any convenient place and the hose 46 utilized to discharge the contents of the tub.

25 The improved apparatus is simple in construction, can be inexpensively manufactured and operates effectually for the purposes described.

The preferred embodiment of the invention 30 is disclosed in the drawing and set forth in the specification, but it will be understood that any modifications within the scope of the claims may be made in the con-

struction without departing from the principle of the invention or sacrificing any of 35 its advantages.

I claim:

1. In an apparatus of the class described, a supporting frame open at the ends and having a plurality of supporting legs, a closed water tank within said frame, a discharge pipe connected into the bottom of the water tank through the open bottom of the frame, and extended laterally between one pair of said legs, feed pipes connected into 45 said water tank in spaced relation, a generator, connecting means between said generator and said feed pipes, and means for supplying water to said water tank.

2. In an apparatus of the class described, 50 a supporting frame open at the ends and having a plurality of supporting legs, a closed water tank within said frame, a discharge pipe connected into the bottom of the water tank through the open bottom of the 55 frame, and extended laterally between one pair of said legs, feed pipes connected into said water tank in spaced relation, a generator, connecting means between said generator and said feed pipes, a receptacle, and conducting means between the discharge pipe of the water tank and the receptacle.

In testimony whereof I affix my signature hereto.

ELMO J. BUSH.
